CLUTCH MECHANISM FOR POWER OPERATED PORTABLE TOOLS

Charles W. Ripsch and Bernard H. Wuebhen,
Dayton, Ohio, assignors to The Buckeye Portable Tool Company, Dayton, Ohio, a corporation of Ohio

Application January 12, 1934, Serial No. 706,416

3 Claims. (Cl. 192—56)

This invention relates to clutch mechanism for power operated portable tools, such as are commonly used for running a nut onto or off of a bolt, or for similar purposes. The present invention is in the nature of an improvement on the clutch mechanism shown and claimed in the application of Ripsch, Bennett, Sandel and Price, filed August 12, 1933, Serial No. 684,796. In the apparatus of that application power is transmitted from the power unit to the front driving member, which is connected with the wrench or other tool to be operated, through the medium of a coiled spring which can be operatively rotated in a forward direction only. Consequently the wrench or other tool could not be rotated in a reverse direction, for the purpose of removing a nut or for like purposes.

One object of the present invention is to provide an apparatus of this kind by means of which the wrench or other tool may be operated in either direction.

A further object of the invention is to provide such an apparatus which will be very simple in its construction, in which the reversing mechanism will not in any way interfere with the forward operation of the apparatus, and which will add little to the cost of the apparatus.

A further object of the invention is to simplify the connection between the driving spring and the front driving member and to facilitate the assembly of the apparatus.

Other objects of the invention will appear as the apparatus is described in detail.

In the accompanying drawing Fig. 1 is a longitudinal sectional view taken through an apparatus embodying our invention, a part only of the power unit being shown; Fig. 2 is a transverse sectional view taken on the line 2—2 of Fig. 1; Fig. 3 is a transverse sectional view taken on the line 3—3 of Fig. 1; Fig. 4 is a transverse sectional view taken on the line 4—4 of Fig. 1; and Fig. 5 is an elevation of the mechanism for connecting the front driving member with the power unit, looking in the direction of the arrow 5 in Fig. 1.

In this drawing we have illustrated one embodiment of our invention and have shown the same as embodied in a power operated wrench of the type shown in the above mentioned application but it will be understood that the invention may take various forms and may be embodied in power operated tools of various kinds.

The particular apparatus here illustrated comprises a power unit which includes a casing 10 having mounted therein a rotatable member, such as a gear 11, which is driven by a suitable motor which is preferably mounted within the casing, but is not here shown. This rotatable member or gear is connected by a tubular shaft 12 with a clutch member 13. Rigidly connected

to and forming a part of the casing 10 is a forwardly projecting tubular structure or extension 14 which encloses the clutch member 13 and is adapted to support the driving mechanism for the tool.

Mounted within the tubular extension 14 is a tubular front driving member 15, the extension being provided with a bushing 16 in which the driving member is mounted for both rotary movement and for axial movement with relation to the power unit. At its forward end this front driving member is provided with means for connecting the same with the tool or other device to be operated and in the present instance, it is provided with a chuck 17 to receive the shank 18 of a tool, such as a wrench 19. The rear end portion of the front driving member is enlarged to provide a recess having a front wall or shoulder 19 and a longitudinal circumferential flange 20. Mounted at the rear end of the front driving member is a rear driving member which, in the present construction, is mounted in the rear end of the tubular front driving member and, as here shown, this rear driving member comprises a head 21 mounted in the recess at the rear end of the front driving member and engaging the shoulder 19. The front portion of the rear driving member is of reduced diameter, as shown at 22, and fits within the body portion of the tubular front driving member. This rear driving member is thus capable of rotation with or with relation to the front driving member.

Mounted within the tubular front driving member is a longitudinal spindle 23, the forward end of which is mounted in and rigidly secured to the front end of the front driving member, as by means of a pin 24. The rear end of the spindle is rotatably mounted in a bearing 25 in the rear driving member and is held against axial movement with relation thereto by a shoulder 26 on the spindle, which engages the front end of the bearing 25, and a nut 27 mounted on the spindle and engaging the rear end of the bearing 25. Mounted about the spindle 23 for longitudinal movement with relation thereto is a member which forms a part of the slip connection between the rear driving member and the front driving member and which, in the present construction, also forms a support for another part of the slip connection. In the arrangement shown this supporting member comprises a sleeve 28 having at its forward end means for connecting the same with the front driving member to cause the latter to rotate therewith but which will permit of the axial movement of the supporting member with relation to the driving member. As here shown this means is in the form of laterally extending parts or lugs 29 secured to and preferably formed integral with the front end portion of the supporting

member or sleeve 28. These laterally extending lugs may be connected with the front driving member in any suitable manner, as by inserting the same in slots in the driving member. Preferably the slots are formed between parts extending inwardly from the wall of the front driving member and, in the construction here shown, the front driving member is provided with an integral collar 30 which is slotted at 31 to receive the lugs. Thus the supporting member or sleeve may be inserted in the tubular driving member from the rear end thereof and operatively connected therewith.

Mounted within the supporting member or sleeve 28 and coiled about the spindle 23 is a spring 32 which is confined between the rear end of the sleeve and a nut 33 mounted on the front portion of the spindle 23. Preferably a collar 34 is loosely mounted about the spindle 23 and serves to centralize the sleeve 28 with relation thereto, and to provide a bearing surface for the nut 33. By adjusting the nut on the spindle the tension of the spring 32 may be varied. The nut may be held in its adjusted positions by any suitable means and we have here shown a resilient band 35 mounted about the front driving member and having a lip 36 extending inwardly through a slot 37 in the wall of the front driving member to engage any one of a series of notches 38 in the head 30 of the nut. In the present instance, the slot 37 forms an extension of one of the slots 39 which are formed in the wall of the front driving member in the operation of slotting the integral collar 30.

35 The rear driving member may be connected with the front driving member in any suitable manner which will cause the two members to normally rotate in unison but which will permit the rear driving member to rotate with relation to the front driving member when excessive resistance is offered to the rotation of the latter. For this purpose there is preferably arranged within the front driving member an annular part which is connected with the rear driving member, 40 extends about the sleeve 28 and is adapted to engage parts carried by the sleeve, such as the lugs 29. The annular part has a slip connection with the laterally extending parts of the sleeve, as by providing the same with opposed cam surfaces which will cause the parts to normally rotate in unison but which will cause the sleeve to yield and permit the annular part to rotate with relation thereto when excessive resistance is offered to the rotation of the sleeve, as would result 45 from the tightening of a nut. The continued rotation of the annular part with relation to the sleeve parts will cause the latter to be subjected to a succession of blows which will be transmitted to the nut to drive the same to its final position.

60 In the particular construction here illustrated there is mounted within the tubular front driving member a coiled driving spring 40, the upper end of which is connected with the rear driving member 21 for rotation therewith in a forward direction.

65 In the present arrangement the inwardly extending portion 22 of the rear driving member is shaped to conform to the contour of the rear end of the spring 40 and is provided with a shoulder 41 which engages the end of the rearmost winding 70 of the spring. The front end of the spring 40 has a slip connection with the front driving member so that the latter will be caused to rotate normally therewith but which will permit the spring and the rear driving member to rotate with relation to the front driving member when excessive

resistance is offered to the rotation of the latter. In the preferred construction a spring seat 42 is provided for the front end of the spring 40 and is in the form of an annular member arranged within the front driving member and supported on the laterally extending parts 29 of the supporting sleeve 28. This spring seat may be of any suitable character but is preferably shaped to conform to the contour of the front end of the spring and is provided with a shoulder 43 which will be engaged by the end of the front winding of the spring, thus causing the rear driving member, spring and spring seat to normally rotate as a unit. As has been stated, the spring seat 42 rests upon the laterally extending lugs 29 of the supporting sleeve 28, and it is provided on its front surface with cam lugs 44 adapted to engage and cooperate with the lugs 29, the upper corners of which are beveled as shown at 45, to provide cam surfaces. The cam surfaces 44 and 45 are of such a character that in the normal operation of the driving mechanism the supporting sleeve and consequently the front driving member which is connected with that sleeve will be caused to rotate with the spring seat, but when excessive resistance is offered to the rotation of the front driving member the spring 32 in the supporting sleeve will yield to permit the cams of the spring seat to ride over the supporting lugs 29.

30 The rear driving member may be connected with the power unit in any suitable manner and preferably this connection is controlled by the longitudinal movement of the driving member with relation to the power unit. As here shown, the head 21 of the rear driving member is provided with clutch jaws 46 adapted to cooperate with the jaws of the clutch member 13 carried by the power unit. The clutch members 13 and 46 are held normally in their separated positions, this being preferably accomplished by a spring 47 pressed plunger mounted in the hollow shaft 12 and engaging the rear end of the spindle 23.

35 If desired, a sleeve 60 may be arranged within the driving spring 40 to contact with the convolutions thereof and prevent the lateral distortion 41 of said spring.

In the operation of the apparatus the wrench, or other tool 18 is engaged with the nut, or other work, the motor being in operation, and forward pressure exerted upon the power unit which causes the same to move forwardly with relation to the driving members and thus operatively engages the two clutch members and causes the rear driving member to be rotated by the motor. This rotary movement is transmitted through 50 the spring 40, spring seat 42 and supporting lugs 29 to the front driving member and tool. So long as the nut runs freely upon the bolt the several parts of the driving mechanism will rotate in unison but as the nut is tightened down and 55 additional resistance is offered to the rotation of the front driving member, this resistance will overcome the tension of the spring 32, thus permitting the supporting members 29 to be moved forwardly by the cam action of the spring seat 60 42 and the cam lugs 44 on the spring seat will ride over the lugs 29 of the supporting member and will then again be moved forwardly so that they will again engage the lugs at the end of a half rotation of the spring seat. The lugs on 7 the spring seat will engage the lugs 29 with a severe impact which will tend to further tighten the nut and will then again ride over the lugs. Usually the spring seat is permitted to make several rotations in this manner so that the sup- 7

porting lugs 29 will be subjected to a series of impacts which will fully tighten the nut. When this has been accomplished the pressure on the tool is relieved to separate the clutch members 5 13—46 and the wrench then removed from the nut.

It will be apparent that if the rear driving member is rotated in a reverse direction and substantial resistance is offered to the rotation of 10 the front driving member, the rear driving member will merely ride over the end of the spring 40, moving the same axially of the driving member but imparting no driving movement thereto. Consequently a mere reversal of the driving motion 15 will not operate the wrench in a reverse direction. It is desirable that the apparatus shall be of such a character that it can be used for running a nut onto a bolt and also for running a nut off of a bolt which, of course, requires a 20 reversal of the direction of rotation of the wrench. In order to accomplish this result I have provided other means for connecting the front driving member and wrench with the power unit, this mechanism being preferably of such a 25 character that the reverse rotation of the front driving member will be entirely independent of the driving spring 40. In the particular construction here illustrated the rear driving member is utilized as a part of the driving connection 30 between the front driving member and the motor, when the tool is to be operated in a reverse direction, and the mechanism is of such a character that the connection will be automatically established when the rear driving member 35 is rotated in a reverse direction. Preferably a one-way clutch is interposed between the rear driving member and the front driving member and so arranged that it will be completely inoperative when the rear driving member is rotated 40 forwardly but will establish a tight connection between the rear driving member and the front driving member when the rear driving member is rotated in a reverse direction. In this particular construction the head 21 of the rear driving member, which is supported within the recess in 45 the rear end of the front driving member, is provided with a series of tapered recesses 48 adapted to receive clutch members, such as rollers 49. The recesses are so arranged that when the rear driving member is rotated forwardly the clutch rollers 49 will move to the larger ends of the recesses and will be inoperative but when the rear driving member is rotated in a reverse direction these clutch members will be moved into wedged 50 engagement with the walls of the recesses and the flange 20 of the front driving member, thus establishing a positive and direct connection between the two driving members. The rear driving member may be rotated in a reverse direction 55 by any suitable means but ordinarily this will be accomplished by merely reversing the direction of operation of the motor forming a part of the power unit. When the wrench has been placed in engagement with a nut and the motor reversed 60 the reverse operation of the rear driving member will move the small ends of the recesses toward the rollers and cause the same to be gripped between the walls of the recesses and the flange and there will be some slight movement of the 65 rollers after they have engaged both the flange and the walls of the recesses. As a result the power will be applied to the wrench gradually, the rear driving member having a slight movement after the wrench has gripped the nut. 70 Consequently a considerable part of the shock

due to the action of the wrench on a tightly seated nut will be absorbed in the one way clutch, thus relieving the operator's arm of the shock or strain which results from a sudden application of power to the wrench when the latter is engaged with a tightly seated nut. 5

While we have shown and described one embodiment of our invention we wish it to be understood that we do not desire to be limited to the details thereof as various modifications 10 may occur to a person skilled in the art.

Having now fully described our invention, what we claim as new and desire to secure by Letters Patent, is:

1. In a power operated portable tool, a rear driving member, means for rotating the same, a tubular front driving member having parts extending inwardly from the wall thereof and spaced one from the other to form longitudinal slots, a supporting member adapted to be inserted in said front driving member from one end thereof and having integral lugs extending into said slots, a spring acting on said supporting member to move the same rearwardly, a driving spring arranged within said front driving member and connected with said rear driving member for rotation thereby, and a spring seat mounted about said supporting member, supported by said lugs and connected with said driving spring for rotation thereby, said spring seat and said lugs having opposed cam surfaces to form a slip connection between the same. 15 20 25 30

2. In a power operated portable tool, a rear driving member, means for rotating the same, a tubular front driving member having longitudinal guideways, a spindle rigidly secured at its forward end to said front driving member and rotatably mounted in said rear driving member, a sleeve mounted about said spindle for movement lengthwise thereof and having lugs extending into said guideways, a spring coiled about said spindle within said sleeve and acting on said sleeve to move the same rearwardly, a nut threaded onto said spindle beyond the outer end of said spring, a collar slidably mounted in said sleeve between said spring and said nut, a driving spring arranged within said front driving member and connected with said rear driving member for rotation thereby, and an annular member mounted about said sleeve, supported by 40 45 50 said lugs and connected with said driving spring for rotation thereby, said annular member and said lugs having opposed cam surfaces to form a slip connection between the same. 40 45 50

3. In a mechanism of the character described, 55 a rear driving member, means for rotating the same, a tubular front driving member, an annular part mounted in said front driving member and connected with said rear driving member for rotation thereby, a member mounted in said front driving member for axial movement with relation thereto, lugs rigidly secured to said axially movable member, said lugs being of such radial length that said axially movable member 60 may be inserted in said front driving member from the rear end thereof, said front driving member having inwardly extending parts to form guideways for said parts and to cause said front driving member to rotate therewith, said lugs and 65 said annular part having opposed cam surfaces to form a slip connection between said driving members. 70
